KNOB

John R. Morgan, Wheeling, Ill., assignor to Amerock Corporation, Rockford, Ill., a corporation of Illinois

Filed Dec. 13, 1962, Ser. No. 72,846

Term of patent 14 years

(Cl. D10—8)

FIGURE 1 is a front elevational view of a knob embodying my new design.

FIG. 2 is a side view of the knob.

FIG. 3 is a perspective view of the knob.

FIG. 4 is a fragmentary sectional view taken along the line 4—4 in FIG. 1.

The design for a knob disclosed and claimed herein is characterized by the specific peripheral configuration of the body portion thereof together with the cone-shaped element and groove on the face of said body portion.

I claim:

The ornamental design for a knob, substantially as shown and described.
